UNITED STATES PATENT OFFICE.

FLORENCE EHRENBERG, OF SPOKANE, WASHINGTON.

SLEEPING-GARMENT.

1,370,009.

Specification of Letters Patent.

Patented Mar. 1, 1921.

Application filed January 29, 1920. Serial No. 354,810.

To all whom it may concern:

Be it known that I, FLORENCE EHRENBERG, a citizen of the United States, residing at Spokane, in Spokane county and State of Washington, have invented certain new and useful Improvements in Sleeping-Garments, of which the following is a specification.

The present invention relates to an improved sleeping garment designed especially for juniors or infants, but equally applicable for use by seniors and adults, and providing a sanitary, comfortable, and convenient sleeping bag or envelop for either outdoor or interior sleeping.

15 The primary object of the invention is the provision of a device of this character that will entirely envelop the sleeper, (as a child) below the neck, leaving the head and face free and uncovered, but incasing the 20 body and limbs, and at the same time leaving them free to turn or move in manner natural for children. The invention contemplates a garment that may readily be laundered; that may with quickness and des- 25 patch be slipped on over the head, and may with equal facility be taken off the wearer, and which, when in place may be fastened and secured to provide adequate protection, and also be attached to the sleeper's bed to 30 prevent entangling by a restless sleeper.

With these ends in view the invention consists in certain novel combinations and arrangements of parts as will be herein- 35 after specified and set forth in the appended claim, and as depicted in the accompanying drawings, wherein I have illustrated one complete example of the physical embodiment of my invention constructed ac- 40 cording to the best mode I have so far de- vised for the practical application of the principles of my invention.

Figure 1 is a plan view of the garment for juvenile use, showing the bottom or base flap turned partly open for convenience of 45 illustration.

Fig. 2 is a perspective view depicting the sleeping garment in use with its lower corners folded back over the front of the envelop for additional protection to the lower 50 extremities of the child, and exemplifying the manner of temporarily attaching the garment to the crib or bed.

Fig. 3 is a vertical sectional view of the garment in position for use.

55 In the preferred form of the invention illustrated in the drawings, the garment is

made up of a single piece of material, which material varies in weight for winter, summer, or medium weight; and comprises an envelop or bag closed at the top and open- 60 able at the lower portion, the front of garment being indicated as 1 while the back is indicated at 2. In the manufacture of the garment the single, rectangular strip, is folded as indicated and at the sides is 65 stitched as at 2', and the neck opening 3 is cut in the longitudinal center of the material to form an aperture for the neck at the unstitched fold at the top of the garment, the placket 4, which may be buttoned, pro- 70 viding additional space for slipping the garment down and up over the head of the wearer in putting it on or taking it off.

In folding the strip of material prior to stitching at the sides, one fold is made pur- 75 posely longer than the other in order that a flap 5 may be fashioned to close the lower open end of the garment, the flap prefer- ably being an extension of the fold that forms the back 2 of the garment, and this 80 flap, as will be apparent from an inspection of the drawings is designed to be folded around the lower end of the bag and over the bottom of the front 1, closing the lower opening, after the garment has been adjust- 85 ed in place.

The flap is hemmed as at 5' to reinforce its free end and along the hemmed edge a suitable number of regularly spaced loops 6 are attached to be fastened over the comple- 90 mentary buttons 7 sewed at the proper points and locations on the face of the front 1, and by securing these loops and buttons the flap may be held in folded position to form a comfortable closure for the lower open end 95 of the garment to shield the lower extremities from the atmosphere.

In addition to the warmth and comfort secured by the double thickness of material at the lower front of the garment, this may 100 be supplemented by folding inwardly the lower corners of the garment, as indicated in Fig. 2, and now these folds are temporarily attached to the front 1 of the garment by utilizing the pair of oppositely disposed 105 loops 8, 8, which project outwardly from the corners of the garment from under the flap and may be slipped over the single button 9 attached or sewed to the front of the garment about centrally thereof. These 110 added folds provide additional thickness of material with consequent warmth and pro-

tection for the lower limbs of the child using the sleeping garment.

To enable the restless child to move and turn within the envelop, and prevent the garment being tangled or wrapped about the wearer, strings 10 are provided at the upper corners for tying to the posts of the crib, as in Fig. 2, and the pin tabs 11, spaced at regular intervals along the lateral edges of the garment may be utilized to fasten, as by pins, to the bed or mattress, also as shown in Fig. 2. By these devices the garment may be held in extended position and so maintained in spite of the movements of a restless sleeper, thus permitting freedom of movement without likelihood of disarranging the garment or uncovering the wearer.

In order that the garment may be rendered sanitary and afford proper protection against permanent defacement or soiling of the bed or mattress, an inner pocket 12 is provided, of the shape indicated in dotted lines and sewed to the back or back wall of the garment. The pocket is open at the lower end adjacent the lower open end of the garment so that a rubberized cloth or other sheet impervious to moisture may be inserted therein, and then the pocket is buttoned or closed by using the attachment 13 shown in dotted lines Fig. 1. For laundrying the rubberized, or sanitary sheet may be withdrawn and washed or cleansed in suitable manner, and of course the garment may

be inverted or turned inside out for laundrying purposes.

From the above description taken in connection with my drawings it is apparent that I have devised a sleeping garment that adequately fulfills all the requirements of a comparatively perfect device, that is warm, comfortable, convenient for putting on or taking off, and one which is simple in construction and comparatively inexpensive of production.

What I claim as new and desire to secure by Letters Patent is—

A one-piece sleeping garment having a closed top, stitched sides, a neck opening and a short central placket, the back of the garment formed with a lower extension flap to fold over in front and close the lower open end of the garment, loops on the free edge of the flap and complementary buttons on the front of the garment, additional loops at the lower corners of the garment for attachment to a centrally located button on the front of the garment when said lower corners are folded over the front of the garment toward each other, said garment having an interior pocket on its back wall for the reception of a sanitary sheet, and attaching devices along the edges of the garment for connection with a bed as described.

In testimony whereof I affix my signature.

FLORENCE EHRENBERG.
